(57) **CLAIM**

The ornamental design for a stroller for a bass violin, as shown and described.

DESCRIPTION

FIG. 1 is a perspective view of a stroller for a bass violin showing my new design with the bass violin being shown by broken lines which are for illustrative purposes only, forming no part of the claim;

FIG. 2 is a perspective view with the bass violin not shown; FIG. 3 is a left side elevational view of FIG. 2 with the straps extending straight out from the carriage;

FIG. 4 is a right side elevational view of FIG. 2 with the straps extending straight out from the carriage;

FIG. 5 is a top view of FIG. 2 with the straps tucked under the carriage;

FIG. 6 is a front view of FIG. 2 with the straps laying on top of the carriage;

FIG. 7 is a rear view of FIG. 2 with the straps laying on top of the carriage; and,

FIG. 8 is a bottom view of FIG. 2 with the straps extending straight out from the carriage.
